CLAIM

The ornamental design for box lantern, as shown and described.

DESCRIPTION

FIG. 1 is a downward-looking, perspective view of a box lantern, according to a first embodiment;

FIG. 2 is an upward-looking, perspective view, according to the first embodiment, showing a first bottom feature in broken lines;

FIG. 3 is an upward-looking, perspective view, according to the first embodiment, showing a second bottom feature in broken lines;

FIG. 4 is a left side view, according to the first embodiment;

FIG. 5 is a front view, according to the first embodiment;

FIG. 6 is a top view, according to the first embodiment;

FIG. 7 is a bottom view, according to the first embodiment, showing the first bottom feature in broken lines;

FIG. 8 is a downward-looking, perspective view of a box lantern, according to a second embodiment;

FIG. 9 is an upward-looking, perspective view, according to the second embodiment, showing a first bottom feature in broken lines;

FIG. 10 is an upward-looking, perspective view, according to the second embodiment, showing a second bottom feature in broken lines;

FIG. 11 is a left side view, according to the second embodiment;

FIG. 12 is a front view, according to the second embodiment;

FIG. 13 is a top view, according to the second embodiment; and,

FIG. 14 is a bottom view, according to the second embodiment, showing the first bottom feature in broken lines.

The broken lines immediately adjacent the shaded areas represent the bounds of the claimed design while all other broken lines are directed to environment and are for illustrative purposes only; the broken lines form no part of the claimed design.
